UNITED STATES PATENT OFFICE.

CHARLES DOERING, JR., OF CHICAGO, ILLINOIS.

LIQUID-DISPENSING APPARATUS.

1,210,612.

Specification of Letters Patent.

Patented Jan. 2, 1917.

Application filed April 26, 1915. Serial No. 23,929.

To all whom it may concern:

Be it known that I, CHARLES DOERING, Jr., a citizen of the United States, and resident of Chicago, in the county of Cook and State of Illinois, have invented certain new and useful Improvements in Liquid-Dispensing Apparatus, of which the following is a description, reference being had to the accompanying drawings, which form a part of my specification.

My invention relates to an apparatus adapted to be put into operative condition through the action of a suitable coin inserted therein, whereby liquids or beverages, in predetermined quantities, may be measured out or dispensed through proper operation of the apparatus; the purpose of the invention being to provide a simple and efficient construction adapted to withstand improper manipulation and which will be positive in its operation when provided with a suitable coin; the apparatus being adapted for use in connection with any liquid-holding vessel or receptacle.

In the drawings, Figure 1 is a side elevation of my improved apparatus shown secured to a liquid-holding receptacle, only a portion of the latter being shown. Fig. 2 is a vertical sectional view of the apparatus, taken on the line 2—2 of Fig. 4, and looking in the direction of the arrows. Fig. 3 is a side elevation of the lower or valve-portion of the apparatus, showing the coin-receiving side thereof with the side wall or cover removed, taken on the line 3—3 of Fig. 4, as indicated by the arrows. Fig. 4 is a longitudinal sectional view taken on the line 4—4 of Fig. 3, looking in the direction of the arrows. Fig. 5 is a vertical sectional view taken on the line 5—5 of Fig. 4 looking in the direction of the arrows, with one of the disks removed. Fig. 6 is a detail sectional view of the valve shown in one of its positions, namely the position for draining the liquid from the liquid receptacle. Fig. 7 is a detail view of the valve and operating mechanism, the latter being shown in side elevation.

My apparatus is intended for use in connection with any suitable liquid-holding vessel or receptacle, such as barrels, kegs, and the like; a portion of a vessel being illustrated at 10 in Fig. 1, mounted on any suitable stand or support indicated at 11. The apparatus contemplates the liquid being fed thereto through the action of gravity, and, there-

fore, is secured to the vessel or receptacle 10 at a point adjacent the lower part thereof. The attachment is adapted to be made by means of a suitable supply tube or pipe 12, the free end whereof is shown threaded so as to permit the apparatus to be removably secured to the receptacle. In order to permit a proper flow of the liquid or beverage into the receiving or measuring portion of the apparatus, through the action of gravity, the supply tube or inlet member 12 is preferably bent downwardly, as indicated, so that the upper portion of the receiving portion of my improved apparatus will be substantially in the same horizontal plane as the lower part of the liquid or beverage-holding receptacle 10. The lower end of tube or pipe 12 connects with a suitable valve-housing or casing 13, which is somewhat in the nature of an inverted T, so as to provide the three passages or ports 14, 15 and 16, see Figs. 2 and 6; member 12 being in communication with port 14. The port or passage 15 extends upwardly and preferably terminates in a flared orifice 15^a. The orifice 15^a communicates with a suitable measuring vessel or member 17, secured thereon. The receiving member or vessel 17 comprises a glass portion suitably incased, thus enabling the manipulator to see the flow of the liquid. The glass vessel or tube is held in proper position by a metallic casing or open-sided housing. The lower or rim portion 19 of the metallic casing is adapted to screw onto the upwardly presented portion of the valve-housing 13, as indicated at 20; the sides of the metallic housing or casing is formed so as to provide open or cut-out portions, and the side metallic portions of the outer casing, shown at 21 in Fig. 1, terminates at their tops in the dome-portion 22. In order to effect proper fluid-tight connections between the cylindrical glass portion and the metallic portions at both ends thereof, I provide the washers or gaskets 23 and 24 at the lower and top sides of the receiving member 17, as shown in Fig. 2; the washer 23 at the lower end of the cup being arranged on the flared wall of the orifice 15^a so that when the metallic casing or wall of member 17 is firmly screwed down on the upwardly presented portion of the valve-casing, the washers 23 and 24 will be compressed between the ends of the glass cylinder or wall and the valve-casing at the lower end and between the

glass cylinder and a suitable flange 22^a provided on the interior of the dome-portions 22.

- In order to permit the proper flow of liquid into the receiving-member 17, it is necessary to provide means for ingress and egress of air. As an exemplification of one form of such means, I show the dome-portion 22 provided with a depending boss 25, 5 having a port 26 extending therethrough. Suitably secured to the boss 25, for example, by being screwed thereon, is a valve-casing or ferrule 27 having radially disposed ports 28. The ferrule or casing 27 is provided 10 with a suitable valve as at 29 normally in contact with the lower part of the ferrule or casing 27. The valve 29 is provided with a depending stem 30, to which is secured a suitable float-member 31. In order that 15 the float-member 31 may be adjusted into different planes within the receptacle or receiving-member 17, the stem 30 is shown threaded and the float-member adjustably held on the threaded stem in any suitable 20 manner. The inner orifice of port 26 is preferably flared, as indicated, so as to provide a proper seat for the valve 29 when the latter has been forced upwardly into 25 closed position.
- 30 The valve-casing or housing 13 is provided with a valve 32 preferably of the tapered cylindrical type, provided with the intersecting, right angularly disposed ports 33 and 34, see Figs. 2 and 6, which, when the 35 valve is properly operated, will alternately register with the passages 14 and 15 and with passages 15 and 16, respectively.

The valve 32 is provided with trunnions 32^a and 32^b; the trunnion 32^a being preferably screw-threaded so as to receive a suitable nut 35. Surrounding the trunnion 32^a is a coil-spring 36 which presses against nut 35 and against a suitable washer 37 which is also mounted on the trunnion 32^a 45 and fits against the side wall of the valve-casing 13, see Fig. 4. By screwing nut 35 onto the trunnion 32^a, spring 36 is compressed against the washer 37, thereby yieldingly maintaining valve 32 in proper position; any slight wear of the valve and valve-seat being taken care of by the action of spring 36, which tends to move the valve 32 toward the spring end, as is clearly 50 evident, thus maintaining a liquid-tight connection.

The trunnion 32^b receives the shank 38 of hand wheel or operating member 39 and provides a pivotal point for the hand wheel 39. The shank terminates in a flange 38^a 55 to which is secured a disk 40 which is preferably provided with a segmental flange 40^a, see Figs. 3, 4 and 5 for a predetermined distance adjacent the periphery of the disk 40.

60 The disk 40 carries a suitable pawl 41

which is pivotally mounted at 42. The pawl 41 is double ended, being in the form of a bell-crank lever, with one end of the pawl provided with an extension or lug 41^a adapted to pass through the arcuate slot 43 70 in disk 40. The extension or lug 41^a on the pawl 41 has a spring 44 secured thereto on the opposite side of the disk 40, as shown in Fig. 3; the other end of the spring 44 being suitably secured to the disk 40 at the 75 point 45, see Fig. 3. The tendency of spring 44 is to hold the pawl 41 in the normal position illustrated in Figs. 3 and 5, namely with the extension or lug 41^a at the lower end of arcuate slot 43.

80 The enlarged end of valve 32 is provided with a circular flange 46, either made integral therewith or rigidly secured thereto, shown in Figs. 4 and 7 and in dotted lines in Figs. 3 and 5. The periphery of the 85 flange 46 is provided with a segmental cut-away portion or groove 46^a, see Fig. 7, and shown in dotted lines in Figs. 3 and 5. The pawl 41 is so pivoted on the disk 40 that it will engage with the ends of the slot 46^a, 90 so that rotation of disk 40, induced through rotation of hand-wheel 39, will, under certain conditions, impart movement to disk 46, and, therefore, to valve 32. The pawl 41 is normally held in the position indicated 95 in Figs. 3 and 5, namely with the end, to which spring 44 is secured, extending into the segmental groove 46^a. It is evident from this construction that movement of the hand-wheel 39 toward the right in Fig. 3, 100 before a coin has been inserted, will cause the disk 40, carrying pawl 41, to rotate toward the right in Fig. 3 without imparting movement to disk 46 secured to valve 32, because the free or coin-engaging end 41^b 105 will be in such position as to move freely across the outer periphery of disk 46 without engaging the shoulder or adjacent end of the groove 46^a. On the other hand, movement in the opposite direction of disk 40 110 would bring the spring-controlled end 41^a of the pawl 41 into engagement with the shoulder or opposite end of the segmental groove 46^a in disk 46 and cause the latter, together with valve 32, to rotate in a similar 115 direction as disk 40, if valve 32 has previously been moved from its normal or draining position illustrated in Fig. 3.

The mechanism just described is inclosed by the cover-plate 47, see Fig. 4, which is 120 so formed as to provide a chamber. The cover-plate 47 is preferably removably secured to the annular portion 13^a of the valve-case 13; the latter being shown provided with bolt-receiving lobes at 13^b, which receive bolts whereby the cover-plate 47 125 may be secured in place. The cover-plate 47 is also provided with a coin-receiving chute 48, see Figs. 3, 4 and 5, which is so formed as to induce the coin to roll down 130

into the chamber formed by the cover-plate 47 in the manner as illustrated in Fig. 3 where a coin is indicated at A. The coin A is permitted to enter the chamber in the manner shown in Fig. 3 when the disk 40 has been rotated so as to bring the segmental flange 40^a into the position shown in Figs. 3 and 5, that is, away from the inner orifice of the passage in chute 48. The flange 40^a prevents a coin passing to the opposite side of pawl 41, namely to the left in Fig. 3. Disk 40, as well as hand-wheel 39, are held against complete rotation by the lip 40^b secured to disk 40, see Figs. 3, 4 and 5; the lip 40^b being adapted to engage with the flanged side of cover-plate 47, the latter being segmentally cut away as is also the rim 13^a of valve-case 13, see Figs. 3 and 5. It is evident from the construction that hand-wheel 39 and the correlated parts can merely be given a partial rotation commensurate with the rotation necessary to bring the passages 33 and 34 of valve 32 into register either with ports 14 and 15 or with ports 15 and 16.

If a coin of suitable character has been inserted in coin-chute 48, and hand-wheel 39 has been so rotated as to bring flange 40^a away from the inner orifice of chute 48, namely to the left in Fig. 3, or to the right in Fig. 5, the coin will come into engagement with the free end 41^b of pawl 41 and also with the circumferential wall within the chamber, so that proper or clockwise rotation of hand-wheel 39, as illustrated in Fig. 3, will cause the coin A to become wedged between the circumferential wall of the chamber and the pawl, thereby forcing end 41^b of pawl 41 downward and into engagement with the shoulder or end wall of groove 46^a in disk 46. This will cause the disk 46, together with valve 32, to rotate with disk 40 and hand-wheel 39. The end 41^b of pawl 41 will remain in engagement with the shoulder or end wall of groove 46^a until the hand-wheel 39 and disk 40, as well as disk 46, have been rotated far enough to permit the coin to drop through the slot 49 formed in the bottom 50 of the housing B which surrounds the valve and valve-operating mechanism just described. As the annular rim 13^a and the flange-portion of cover-plate 47 are cut away at the lower sides, the coin is permitted to slide out of the chamber formed by cover-plate 47 and through slot 49.

The housing B is provided with a coin-receiving receptacle C, suitably secured and locked in place by any suitable mechanism that will prevent undue access.

Port 16 of the valve-case 13 is shown provided with a suitable discharge member or spout 51 which extends through the side wall of housing B, as shown in Figs. 1, 2 and 3.

The operation of my improved apparatus is as follows: The tube or pipe 12 having been properly inserted or connected with the liquid or beverage-holding receptacle 10, liquid may then be withdrawn from the receptacle by inserting a suitable coin edge-wise in chute 48 so as to permit it to roll downwardly through the passage. Hand-wheel 39 is then rotated to the right in Fig. 3 so that the coin, as indicated at A, will force the end 41^b of pawl 41 into the groove 46^a and cause valve 32 to rotate with the hand-wheel, the rotation of the latter being limited by means of lip 40^b on disk 40. This rotation of the valve 32 will bring port 33 of the valve into register with port 14 which communicates with pipe or tube 12; while the intersecting or right angularly disposed port 34 of the valve 32 will be brought into register with the port 15 of the valve-casing, thereby establishing communication between the liquid-holding receptacle 10 and the liquid-receiving cup or portion 17; the described position of the various ports being disclosed in Fig. 6. With the valve in the position just described, it will be seen that communication with spout or discharge-member 51 will be closed off. The liquid will flow through the valve and upwardly into liquid-receiving cup or member 17 until it reaches float-member 31 and causes float-member 31 to move upwardly. The upward movement of float member 31 will force ball valve 29 onto its seat 25, and thereby close the air-port 26. With valve 29 in closed position, the further egress of air from liquid-receiving cup 17 will be prevented, and the pressure in the upper part of cup 17 will prevent further flow of liquid from receptacle 10 and through valve 32. Hand-wheel 39 is then rotated in the opposite or counter-clockwise direction, made possible by the previous releasing of the coin A through slot 49. The moment the coin has been discharged into the coin-receiving receptacle C, the spring-controlled end 41^a of pawl 41 will move into engagement with the opposite end of groove 46^a of disk 46 and cause valve 32 to rotate with hand-wheel 39 and disk 40 a distance sufficient to bring port or passage 34 of valve 32 into communication with port 16 of the valve-casing and therefore also with spout 51, while passage or port 33 will be moved into register with the port 15 of valve-casing 13, thereby establishing communication between the receiving portion or cup 17 and the spout 51 and allow the liquid to flow from the cup through the spout and be received by the manipulator. Movement of the valve into registering positions is determined by the lip 40^b on disk 40. With the valve in the position just described, communication with port 14, and, therefore, with pipe or tube 12 and receptacle 10 will be shut off. The

draining or dispensing position of the valve is illustrated in Figs. 2 and 4.

It is evident from the construction shown and described that the quantity of liquid to be dispensed with each insertion of a coin may be controlled or regulated by means of float-member 31; that is, a smaller quantity of liquid will be obtainable when float-member 31 is lowered on the stem 30 of valve 29; 5 because the moment valve 29 is moved upward to its seat 25, the pressure within the cup or receiving portion 17 at the upper end will be such as to prevent further flow of liquid into the cup. It is also apparent 10 from the construction that it is impossible to secure a further supply of liquid without inserting an additional coin, because reverse or clockwise movement of hand-wheel 39 will not cause valve 32 to rotate therewith, so 15 that ports 33 and 34 will not be brought into the position shown in Fig. 6, due to the fact that pawl 41 cannot be tilted without the wedging action of a coin inserted between it and the side walls of the chamber. I have 20 also shown my improved apparatus provided with suitable registering mechanism D which may be of a well known type and suitably mounted on the bottom 50 of the housing B. The operating shaft of the registering mechanism D is shown provided 25 with a suitable arm 52 pivotally connected by means of a link 53 to an arm 54, which latter is rigidly secured to the trunnion 32^a of the valve 32, so that each forward movement of valve 32, into the position assumed 30 when the liquid is being drained from the cup 17, will cause the registering mechanism D to operate and register an operation of the valve. Such registering mechanism may 35 be found desirable to indicate the number of coins that should be contained within receptacle C.

I have shown and described what I believe 40 to be the simplest and best form of my invention, but the construction may be modified in certain respects without, however, departing from the spirit of my invention, and I do not wish to be understood, therefore, as limiting myself to the exact construction shown and described.

What I claim is:—

1. In a liquid-dispensing apparatus, a 45 valve-housing provided with a two-way valve rotatably mounted in the housing and provided with trunnions extending to the outside of the housing, one of the trunnions being provided with a flange having a segmental cut-out portion, an operating member loosely mounted on said trunnion and 50 provided with a circumferential disk held in spaced relation to the valve-housing, a double ended pawl pivotally mounted on said disk with one end normally seated in the segmental cut-out portion of said flange whereby the valve may be rotated in 55

one direction, and means for directing a coin onto the opposite end of said pawl whereby the pawl will be tilted through the action of a coin and said end brought into engagement with the opposite end of said segmental cut-out portion of the flange and thereby enable the valve to be rotated in the opposite direction. 70

2. In a liquid-dispensing apparatus, a valve-housing, a plug-valve rotatably mounted in said housing, said valve being provided with a trunnion extending through to the outside of the housing, a flange secured to said trunnion and provided with a segmental cut-out portion, an operating member loosely mounted on the trunnion and provided with a disk held in spaced relation with the side of the valve-housing, said disk being provided with a segmental flange for closing the space between the disk 85 and the valve-housing to a predetermined extent, a double ended pawl pivotally mounted on the disk so as to have one end of the pawl extending into a vertical plane beyond the vertical plane of one end of said segmental flange, while the other end of said pawl is normally seated in one end of the cut-out portion of the said flange whereby the valve may be moved in one direction through proper rotation of said operating member, and means for guiding a proper coin onto the first-mentioned end of said pawl whereby the latter may be oscillated and said coin engaged-end moved into the segmental cut-out portion of said flange 90 while the other end is removed therefrom so that the valve may be rotated in the opposite direction through proper operation of said operating member. 95

3. In a liquid-dispensing apparatus, a valve-housing provided with a plurality of ports, a plug-valve rotatably mounted in said housing and provided with angularly disposed ports adapted to effect communication between any two selective ports of the plurality of ports in said housing, the end of said valve being provided with a flange having a pair of shoulders arranged in spaced relation, an operating member loosely mounted on the end of the valve and provided with a disk having a segmental flange adjacent its periphery for a predetermined distance, a spring-controlled double-ended pawl-pivoted on the disk in proximity to one end of the segmental flange, one end of said pawl being normally held in engagement with one of the shoulders on said flange so that the valve may be rotated in one direction through proper operation of said operating member, and means for guiding a coin into the space between said disk and the wall of the valve-housing when said disk is rotated to a predetermined position so as to permit the coin to engage with the free end of the pawl and thereby move the 100 105 110 115 120 125 130

latter into engagement with the other shoulder on the flange secured to the valve whereby the valve may be rotated in the opposite direction through proper rotation of the operating member.

4. In a liquid-dispensing apparatus, a valve-housing, a plug-valve rotatably mounted in said housing and provided with a trunnion, a flange secured on said trunnion and provided with a pair of engaging points, an operating member loosely mounted on the trunnion adjacent said flange, a disk secured to said member provided with a stop for limiting the rotation of said operating member and the valve in either direction, said disk being provided with a segmental flange for a predetermined extent adjacent the periphery thereof extending intermediate of the disks and the wall of the valve-housing, so as to close off the intervening space when the disk has been ro-

tated in one direction, a two-ended spring-controlled pawl pivotally mounted on said disk in proximity to one end of said segmental flange, with one end of the pawl extending into a vertical plane beyond the end of the segmental flange, one end of the pawl being normally held in engagement with one of the engaging points, and a coin-receiving chute adapted to direct an inserted coin onto one end of said pawl when the disk is in normal position and said end of the pawl brought into engagement with the other engaging point on said flange through the action of the inserted coin so that movement of the operating member will rotate the valve in the opposite direction.
